VISE

Original application filed June 1, 1927, Serial No. 195,810. Divided and this application filed May 1, 1928.
Serial No. 274,282.

This invention relates to work clamping and holding devices of the type generally termed vises, and is more particularly concerned with a portable tool having means for attachment to a bench, flanged edge and similar supports and providing relatively adjustable vise jaw elements.

A feature of the invention consists in the provision of a portable vise having a support embracing clamp detachably engaged with its fixed jaw in combination with a pair of vise jaws of screw adjustable type constructed and arranged to function as a wrench when detached from said support engaging clamp.

A further feature of the invention consists in the provision of a pair of screw adjustable vise jaws with the relatively fixed jaw provided with a foot extension, in combination with a support embracing clamp mounting a jaw base having a recess to receive and means detachably to clamp said foot extension therein.

Another feature of the invention consists in the provision, in combination with a pair of relatively movable vise jaws, of a clamp base attached to the fixed jaw of said pair of jaws, and a support embracing clamp mounted upon said base for swinging adjustment relatively thereto about an axis substantially at right angles to the line of jaw movement thereby making it possible to use the vise under varying conditions of work and positions of a support relatively thereto.

From another aspect, a feature of the invention may be said to consist in the provision of a portable vise having relatively movable vise jaws and support engaging means attached to the relatively fixed jaw of the pair of jaws and providing a base to support the jaws for movement in a vertical plane in cooperation with a complementary support embracing member which functions also to embrace a support to position said jaws for movement in a horizontal plane.

These and other features and advantages of this invention, which constitutes a division of my application, Serial No. 195,810 for screw adjustable mechanisms, will be

more clearly apparent from the following detailed specification which is to be read in conjunction with the accompanying drawings forming part thereof and in which:

Figure 1 is a view in vertical longitudinal section of the vise of the present invention mounted upon a bench or other support for horizontal movement of its jaws.

Figure 2 is a vertical section through the fixed jaw and support engaging clamp taken on the line 2—2 of Figure 1.

Figure 3 is a longitudinal sectional view through the ratchet wheel head of the adjusting screw and the ratchet-mounting operating handle, the section being taken on line 3—3 of Figure 1.

Figure 4 is a detail in longitudinal section of the sectional head of the ratchet handle in detached and opened position for ratchet reversal.

Figure 5 is a perspective detail of the detached base block of the support embracing clamp which cooperates with and seats on the foot extension of the fixed jaw and connects the latter with the clamp.

In the physical embodiment of the invention, provision is made of a wrench-like structure comprising a jaw 1 having a shank rigid therewith, said shank comprising a relatively large non-circular, and as shown, square in section, inner end portion 2 and a circular outer end portion 3 of less diameter, the extreme outer end of which is further reduced in diameter and screw threaded at 4 (Figure 1). A movable jaw 5 cooperates with the fixed jaw 1 and has a tubular shank 6 which is slidable on the relatively large portion 2 of the shank of the fixed jaw 1 and extends a substantial distance beyond the outer end of said shank portion. The bore of the portion of the shank 6 that is disposed on the portion 2 of the shank of the jaw 1 when the jaws are closed may conform in cross section with the cross sectional configuration of the portion 2 of the shank of the jaw 1 so that the jaw 5 will be held against turning about the axis of the shank of the jaw 1 and the outer end portion of the shank 6 beyond the outer end of the portion 2 of the shank of the jaw 1 may have

its bore formed to be circular in cross section and provided with an internal screw thread as indicated at 7. The confronting portions of the jaws 1 and 5 may have registering cavities therein indicated at 8 and 9, respectively, provided with transverse serrations for gripping small circular objects.

A tubular externally screw threaded adjusting screw 10 is rotatably supported on the relatively small circular portion 3 of the shank of the jaw 1 and at its inner end abuts a bearing washer 11 that is disposed on the portion 3 of the shank of the jaw 1 against the shoulder that is produced at the outer end of the portion 2 of the shank of the jaw 1, the inner end portion of the screw 10 being in threaded engagement with the internally screw threaded outer end portion 7 of the shank 6 of the jaw 5. The outer end portion of the screw 10 is enlarged diametrically to produce an integral ratchet wheel 12 having its periphery curved substantially convexly transversely thereof and formed with a circumferentially spaced series of radial sockets 13. The screw 10 is retained on the portion 3 of the shank of the jaw 1 by a washer 14 which abuts the outer end of the screw and a retaining nut 15. The retaining nut 15 engages the screw threaded extreme end portion 4 of the shank of the jaw 1 and is secured to the latter by a set screw 16.

It is manifest that rotation of the screw 10 in one direction about the axis of the shank of the jaw 1 will cause the jaw 5 to move toward the jaw 1 and that reversal of the direction of rotation of the screw 10 will cause a reversal of direction of movement of the jaw 5 in respect to the jaw 1. A set screw 17 that is carried by the outer end portion of the tubular shank 6 of the jaw 5 may be tightened against the screw 10 to prevent accidental rotation of the screw 10 and consequently to hold the jaw 5 in adjusted position in respect to the jaw 1.

A lever for operating the screw comprises a handle bar 19 and a head for embracing the ratchet wheel 12. Said head comprises a section 20 which is integral with the handle bar and a cooperating section 21 having a short shank 22 adapted to fit in a laterally cut away portion 23 (Fig. 4) on the adjacent end of the handle bar 19 and connected with the handle bar 19 by a transverse pivot element 24. A retaining ring 25 is slidable on the handle 19 to and from position to overlap the shank 22 and to then retain the shank 22 completely in the cut away portion 23 of the handle 19 so that the sections 20 and 21 will be retained on the ratchet wheel 12 and will partially encircle the ratchet wheel 12. The sections 20 and 21 are curved transversely to conform substantially to the transverse curvature of the peripheral portion of the ratchet wheel 12. The free end of the shank

22 and the adjacent wall of the cut away portion of the handle 19 are complementarily beveled so as to produce a relatively large contact surface between the handle 19 and the shank 22 when the shank 22 is completely disposed in the cut away portion 23 of the handle 19. The adjacent ends of the sections 20 and 21 likewise are complementarily beveled so as to fit neatly and firmly against each other when the sections 20 and 21 are closed as shown in Figure 3. When the link 25 has been slid along the handle 19 out of engagement with the shank 22, the section 21 may swing away from the section 20 a distance sufficient to permit removal of the lever from the ratchet wheel 12 as suggested in Figure 4.

The section 21 of the head of the lever is formed with an outwardly extending tubular boss 26 having a head 27 at its outer end formed with the laterally extending flange 28 or marginal edge portion and with a relatively small central opening in axial alignment with a larger opening in the section 21. An actuating pawl 29 extends slidably through the latter opening and has a reduced rigid shank 30 which protrudes from the tubular boss 26 through the opening in the head 27. The outer end portion of the shank 30 is threadedly engaged by an adjusting nut 31 having a laterally extending finger 32 formed with a bent end portion 33 in contact with the edge of the flange 28. Between the nut 31 and head 27 a convexo-concave spring washer 34 having a notched edge is disposed on the shank 30 and limits the inward movement of the pawl 29 in response to the actuation of a compression spring 35 that is coiled about the shank 30 within the confines of the tubular boss 26. The nut 31 can be tightened to expand the spring washer 35 more or less and thereby to permit the pawl 29 to move a greater or less distance toward the center of the head of the lever to respond to the actuation of the spring 35. The extending inner end of the pawl 29 is beveled as indicated and is adapted to enter into one of the sockets 13 in the ratchet wheel 12 when the sections 20 and 21 are closed so that swinging of the lever in one direction about the axis of the shank of the jaw 1 will cause the screw 10 to turn in the same direction on the shank of the jaw 1, and swinging of the lever in the opposite direction about the axis of the shank of the jaw 1 will not cause rotation of the screw 10 for the reason that the beveled face of the pawl 29 will contact with a side wall of the associated socket 13 and will ride out of such socket against the action of the spring 35 onto the periphery of the ratchet wheel 12. In moving the jaws 1 and 5 together, the lever will be arranged on the ratchet wheel 12 so that it will be effective to turn the screw 10 as required to move the jaw 5 toward the jaw 1 and the lever then may

be reversed on the ratchet wheel when it is desired to reversely move the jaws.

The bodily detachable and reversible intermittent grip device above described forms the subject matter of my application, Serial No. 5 274,283, constituting a division of my application, Serial No. 195,810 aforesaid.

In accordance with the present invention, the described vise-jaws and their operating 10 connections are provided with a detachable support-engaging frame which, as shown, includes a substantially U-shaped frame member 36 having a pair of substantially parallel arms 37 and 38, respectively. The 15 free end portion of the arm 38 carries a clamping screw 39 which can be tightened against one face of an edge portion of a table or like support, such as indicated at 40, when the arm 37 is disposed against the opposite 20 face of the support 40, whereby the clamp member 36 will be secured to the support 40. The arm 37 is formed with an extending lug 41 (Figs. 1 and 2) at its free end. The lug 41 is rounded off transversely and is 25 adapted to fit between a pair of spaced lateral ears 42 and 43, respectively, on a supporting block 44. The members 42, 41 and 43 are provided with aligned openings for the reception of a pivot pin 45, whereby the supporting 30 block 44 will be pivotally connected with the lug 41 of the frame member 36, as best seen in Figure 1. The supporting block 44 is formed with a rectangular seat at 440 in which the outstanding head or crown portion 46 of the jaw 1 of the wrench is adapted to fit snugly. A fastening screw 47 has its shank threaded through an opening in a side wall of the seat 440 and can be tightened until the end portion of the shank enters and 35 engages with a socket or depression 48 (Fig. 2) in the adjacent side of the crown portion 46 of the jaw 1 of the wrench, whereby the jaw will be secured firmly to the supporting block 44. The jaw 1 then will serve as the stationary jaw of the vise and the jaw 5 can 40 be adjusted toward and away from the jaw 1. The vise and its supporting block 44 can be swung about the axis of the pivot pin 45 on the arm 37 of the clamp frame 36 for the 45 convenience of the user of the device in disposing the object that is held between the jaws of the wrench in a desirable position and, reversely, the clamp frame can be attached to a support at a desired angle to the line of clamping movement of the vise jaws.

The supporting block 44 has a substantially flat back wall and is formed with extending edge portions 49 as clearly shown in Figure 5. These edge portions 49 are formed 60 with parallel ears 50 at the free end of the block 44 and at the outer sides of slots 51 in the edge portions 49 of the block. A substantially U-shaped extension 52 has a pair of arms 53 formed at their extremities with forwardly extending ears 54 which extend into

the slots 51 and are secured to the block 44 by a transverse pivot element 55. The ears 54 are formed with integral nose portions which project from the slots 51 and act as stops abutting the inner or rear face of the 70 jaw 1 at the outer edges of its head or crown 75 46 when the member 52-53 is disposed at an angle to the back wall of the block 48 as seen in Figure 1. When the rear faces of the arms and web of the extension 52-53 75 are flush with the flat rear face of the block 44, the rear edges of the ears 54 will abut the faces of the portions 49. The block will then have a bearing surface of relatively great area on a flat supporting surface when the 80 block and its extension are disposed on such flat supporting surface preliminarily to the use of the hereinbefore described vise structure with the jaws positioned for vertical 85 movement.

The herein described structure is therefore, when assembled, a complete vise which may be supported in a plurality of positions and angles relatively to its support. With the support-engaging clamp and block detached, it may be packed for storage or shipment in a relatively small space. The clamping jaws of the vise with their operating mechanism when separated from the support-engaging clamp and base may function as a 90 wrench and are described and claimed per se as such, in my copending application, Serial No. 274,284 constituting a division of my original application, Serial No. 195,810 for 95 screw adjustable mechanisms.

While the particular combination of elements herein described and claimed represents a preferable embodiment of my invention, it is intended as illustrative rather than restrictive thereof, and its structural features 100 are susceptible of modification and adaptation to varying conditions in consonance with the spirit of the invention and the scope of the appended claims.

What I claim therefore, and desire to secure by Letters Patent is:

1. A mechanism of the character described comprising a jaw having a shank, a second jaw movable on said shank toward and away from said first jaw, a clamp comprising a U-shaped frame member having a clamping screw threaded through one of the arms thereof for cooperating with the second arm of the substantially U-shaped clamp frame to secure the latter to an edge portion of a table or like support, the second arm of said clamp frame member having an extending lug, a supporting block having a pair of spaced ears straddling said lug of the clamp and pivotally connected therewith, said supporting block having a seat for the partial reception of said first named jaw, and a set screw for securing said first jaw in place in said seat.

2. A mechanism of the character described

- comprising a jaw having a shank, a second jaw movable on said shank toward and away from said first jaw, a clamp comprising a U-shaped frame member having a clamping screw threaded through one of the arms thereof for cooperating with the second arm of the substantially U-shaped clamp frame to secure the latter to an edge portion of a table or like support, the second arm of said clamp frame member having an extending lug, a supporting block having a pair of spaced ears straddling said lug of the clamp and pivotally connected therewith, said supporting block having a seat for the partial reception of said first named jaw, and a set screw for securing said first jaw to place in said seat, said block having a substantially flat face opposite to said seat, a substantially U-shaped supporting member having arms hinged to said block, a stop on said substantially U-shaped supporting member, and spaced stops on said block for cooperating with the stop on the U-shaped supporting member to limit the swinging movement of said substantially U-shaped supporting member between a position substantially at right angles with the flat face of said block and a position in the plane of the flat face of said block.
3. A portable vise comprising a screw adjustable wrench structure providing a fixed jaw having a crown extending outwardly from one face and a shank extending outwardly from the opposite face thereof and a relatively movable clamping jaw mounted for rectilinear movement on the shank of the fixed jaw, an upstanding supporting plate having a recess therein seating and detachably holding said crown of the fixed jaw, and a substantially U-shaped support embracing clamp having the end of one arm hingedly attached to the lower portion of said plate at a point below the operating plane of said jaws.
4. A portable vise comprising a fixed jaw having an elongated shank and an extended head, a relatively movable jaw having a tubular shank enclosing and guiding on a portion of said elongated shank of the fixed jaw and internally threaded in part, a threaded operating sleeve rotatably mounted upon said elongated shank and cooperating with the internally threaded tubular shank to move its jaw toward and from the fixed jaw, means cooperating with said threaded sleeve and manually operable to effect rotation thereof in reverse directions, a base plate having a recess therein seating the extended head of the fixed jaw and having means for detachably holding said plate on said head, a substantially U-shaped support embracing clamp, and means on said clamp and plate providing a pivotal mount for the clamp on the plate below the plane of operating movement of the jaws and about an axis substantially at right angles to said plane of movement of the jaws and about an axis substantially at right angles to said plane of movement, said base plate functioning in combination with said clamp to engage the support embraced thereby with said jaws positioned for relative movements in different planes in right angular relation.
5. A portable vise comprising a fixed jaw having an elongated shank and an extended head, a relatively movable jaw having a tubular shank enclosing and guiding on a portion of said elongated shank of the fixed jaw and internally threaded in part, a threaded operating sleeve rotatably mounted upon said elongated shank and cooperating with the internally threaded tubular shank to move its jaw toward and from the fixed jaw, a base plate seating and detachably gripping the extended head of the fixed jaw, and a substantially U-shaped support embracing clamp pivotally mounted on said base plate beyond the plane of operating movement of said jaws and extending outwardly of said plate, said base plate having an extension pivotally mounted thereon for movement into and out of the plane of the supporting face of said base plate.

stantially at right angles to said plane of movement.

5. A portable vise comprising a fixed jaw having an elongated shank and an extended head, a relatively movable jaw having a tubular shank enclosing and guiding on a portion of said elongated shank of the fixed jaw and internally threaded in part, a threaded operating sleeve rotatably mounted upon said elongated shank and cooperating with the internally threaded tubular shank to move its jaw toward and from the fixed jaw, means cooperating with said threaded sleeve and manually operable to effect rotation thereof in reverse directions, a base plate having a recess therein seating the extended head of the fixed jaw and having means for detachably holding said plate on said head, a substantially U-shaped support embracing clamp, and means on said clamp and plate providing a pivotal mount for the clamp on the plate below the plane of operating movement of the jaws and about an axis substantially at right angles to said plane of movement, said base plate functioning in combination with said clamp to engage the support embraced thereby with said jaws positioned for relative movements in different planes in right angular relation.

6. A portable vise comprising a fixed jaw having an elongated shank and an extended head, a relatively movable jaw having a tubular shank enclosing and guiding on a portion of said elongated shank of the fixed jaw and internally threaded in part, a threaded operating sleeve rotatably mounted upon said elongated shank and cooperating with the internally threaded tubular shank to move its jaw toward and from the fixed jaw, a base plate seating and detachably gripping the extended head of the fixed jaw, and a substantially U-shaped support embracing clamp pivotally mounted on said base plate beyond the plane of operating movement of said jaws and extending outwardly of said plate, said base plate having an extension pivotally mounted thereon for movement into and out of the plane of the supporting face of said base plate.
